GARMENT SUPPORTER

Charles Bartlog, Milwaukee, Wis.

Application April 15, 1935, Serial No. 16,450

4 Claims. (Cl. 241—25)

This invention appertains to garment supporters, and more particularly to a novel form of trouser suspenders.

Generally, suspenders are worn from necessity over the shirt, and during the summer season, when it is desirable to remove the coat and vest, the suspenders present an unsightly appearance, irrespective of attempts to make the same of an ornamental character.

10 It is therefore one of the primary objects of my invention to provide a pair of suspenders, which will effectively support the trousers, and which can be worn under the shirt, and thus be invisible to the eye when the coat and vest are removed.

Another salient object of my invention is to provide a pair of suspenders having novel means for engaging the trouser buttons, and novel means for engaging the skirt of shirt, where- 20 by the skirt will be effectively held so that the riding up of the skirt will be prevented.

A further object of my invention is the provision of a pair of inside trouser suspenders having depending, elongated resilient wire loops carried by the terminals of the spreader tabs for receiving and holding the skirt of the shirt, with hooks at the upper ends of the loops for detachably receiving the trouser buttons, whereby to support the trousers.

30 A further object of my invention is the provision of novel means arranged adjacent to the trouser button-engaging hooks, whereby to prevent the accidental displacement of the buttons from the hooks when the suspenders are being worn.

A still further object of my invention is to provide an improved pair of inside suspenders of the above character, which will be efficient in use, and comfortable to wear, and which can be placed upon the market at a reasonable cost.

40 With these and other objects in view, the invention consists in the novel construction, arrangement, and formation of parts, as will be herein-after more specifically described, claimed, and 45 illustrated in the accompanying drawing, in which drawing:

Figure 1 is a front view showing my improved suspenders in use, parts of the shirt and trousers being shown broken away to illustrate the manner in which the skirt of the shirt is held.

50 Figure 2 is an enlarged detail view illustrating one of the novel supporting members carried by the front of one of the shoulder straps.

Figure 3 is an enlarged detail view illustrating 55 the rear supporting member, the supporting

member being shown applied to the trousers and shirt, only a fragment of the shirt and trousers being shown.

Referring to the drawing in detail, wherein similar reference characters designate corresponding parts throughout the several views, the letter S generally indicates my improved pair of suspenders for supporting a pair of trousers T. As stated, the suspenders are adapted to be worn under the shirt W.

5 In accordance with my invention, the trouser supporting buttons 5 are sewed to the inside of the waistband of the trousers T, and these buttons are located and spaced in the usual manner. The shirt W is of the usual or any preferred type, 15 provided with the ordinary skirt, which is divided to form the tail 6 and the front flaps 7. In order to prevent the bunching of the shirt, and to give the same a neat appearance, I prefer to notch or cut the lower edge of the shirt tail 6, as at 8. 20

25 My improved pair of suspenders S includes shoulder straps 10, which can be substantially of the ordinary type, and the rear ends of the straps are firmly secured together and provided with the centrally disposed depending back strap 11. The shoulder straps 10 can be made adjustable as to length to suit the size of the person wearing the same. The front lower ends of the shoulder straps 10 carry slides 12 for the spreader tabs 13, 30 and the slides are normally held closed by snap fasteners 14. By opening the slides the spreader tabs 13 can be removed from the shoulder straps. The back strap 11 also carries a slide 15 for receiving the rear spreader tab 16, and the rear slide 15 is held closed by snap fasteners 17, so 35 that the spreader tab 16 can be removed from the back strap.

40 The terminals of all of the spreader tabs carry novel means for engaging the shirt and the buttons of the trousers, and each one of these members consists of an elongated depending loop 18 formed from resilient wire. Each loop 18 consists of spaced, substantially parallel legs 19, and a lower connecting bite portion 20. The upper 45 end of one leg is bent at an angle, as at 21, and is provided with an eye 22 for connection with a spreader tab terminal. The other leg 19 terminates below the angular end 21 of the first leg, and said second leg is provided with a right- 50 angularly disposed extension 23, which terminates in a hook 24 for engagement with a trouser button 5. The open end of the hook can be closed by the swinging gate 25, so that after the hook 55 is placed over the button, the gate can be swung

down so as to prevent accidental displacement of the button from its hook.

- In use of my improved pair of suspenders, the front and rear spreader tabs 13 and 16 can be removed from the shoulder straps, if so preferred, and the loops 18 of said tabs can be placed on the inside of the trousers by connecting the hooks 24 thereof with the buttons. The trousers can now be placed on the person, and the shoulder straps swung over the shoulders, after which the slide 15 can be connected with the rear spreader tab 16. The shoulder straps 10 can now be grasped by the wearer, and the front slides 12 can be connected with the front spreader tabs 13. 15 The shirt can now be placed on the wearer, and the tail 6 of the skirt of the shirt is pushed downwardly between the legs 19 of the loops 18, as is clearly shown in Figure 3 of the drawing.
- The front flaps 7 of the skirt of the shirt are now brought forwardly, and are placed between the legs 19 of the loops 18 carried by the front spreader tabs 13. Due to the inherent resiliency of the material from which the loops are formed the same will frictionally engage the skirt of the shirt, and thus effectively prevent the shirt from riding up.
- 20 By providing the depending loops, the skirt of the shirt can be pulled downwardly below the waistband of the trousers, and at the same time 25 the trousers can be effectively supported.

From the foregoing description it can be seen that I have provided an improved pair of inside suspenders, which will not only effectively support the trousers, but which will hold the shirt in a 30 neat and presentable appearance.

Changes in details may be made without departing from the spirit or the scope of my invention, but what I claim as new is:

1. A pair of suspenders adapted to be worn 40 under the shirt comprising a pair of shoulder straps, front and rear spreader tabs carried by the shoulder straps, releasable slides connecting

the spreader tabs with the shoulder straps, whereby said tabs can be removably associated with the shoulder straps, depending elongated resilient shirt-receiving loops carried by the terminals of the spreader tabs, button-engaging hooks on said loops adjacent to the upper ends thereof, and pivoted gates carried by said loops movable over the open ends of the hooks.

2. In a pair of inside suspenders an elongated shirt-receiving loop including a short leg, a long leg, and a resilient connecting bottom bite portion, a right-angularly extending arm on the upper terminal of the short leg, a button-engaging hook on said arm, an angularly extending arm on the upper end of the long leg diverging from the first mentioned arm, a suspension loop on the last-mentioned arm, said arms defining a flaring throat entrance into said loop, and a swinging gate on the first-mentioned arm movable over the open end of said hook.

3. In a pair of inside suspenders, an elongated U-shaped shirt-receiving loop including a short leg, a long leg, and a resilient connecting bite portion, a right-angularly extending arm formed on the upper terminal of the short leg, a button-engaging hook on said arm, an angularly extending arm on the upper end of the long leg diverging from the first-mentioned arm and overlying the same, and a suspension loop formed on the last-mentioned arm, said arms defining a flaring throat entrance into the first-mentioned loop.

4. A pair of inside suspenders comprising shoulder straps, front and rear spreader tabs associated with the shoulder straps, independent resilient elongated U-shaped shirt-receiving loops carried by each terminal of the tabs and depending therefrom, and trouser-button engaging hooks formed on the loops adjacent to the upper ends thereof.

CHARLES BARTLOG.
